UNITED STATES PATENT OFFICE.

GROVER M. REPP, OF NEW YORK, N. Y.

STEREOTYPE-MATRIX-MAKING MACHINE.

Application filed February 28, 1927. Serial No. 171,442.

This invention relates to the art of printing and has particular reference to the means for expeditiously and reliably making stereotype matrices.

5 Whereas in the usual or old practice of matrix making, the flong or plastic mass is forced or worked manually or otherwise upon and into the set-up, such as type, plates, or other original matter, a process involving 10 a tremendous amount of manual labor and time, both of which conditions are of extreme importance in a printing office, by this new process or mechanism the making of the matrices is performed rapidly and with 15 the highest degree of efficiency and perfection and with relatively little manual labor.

Up to the present time the only known method of making a matrix is to lay or place the flong on the type form, then by 20 means of manual labor the flong is subjected to a molding process by means of pressure; then by manual labor the type form with the molded flong thereon is moved onto a hot drying element and allowed to remain 25 until dried into matrix formation. Following this the hot form is removed by manual labor from the drying element, the flong which was previously moist and which has now become the completed dry matrix, is 30 removed from the type form and is suitable for casting stereotype plates therefrom for printing purposes. All this entails a great amount of manual labor and an extreme expenditure of time due to the fact that the 35 type must be handled manually so frequently throughout the process.

Among the objects of this present invention, therefore, is to provide a machine for the making of matrices, the machine being 40 so designed as to operate to a large extent automatically and very rapidly, and with the further qualification that the output is uniformly of a high degree of perfection.

With the foregoing and other objects in 45 view the invention consists in the arrangement and combination of parts hereinafter described and claimed, and while the invention is not restricted to the exact details of construction disclosed or suggested herein, 50 still for the purpose of illustrating a practical embodiment thereof reference is had to the accompanying drawings in which like reference characters designate the same parts in the several views, and in which—

55 Figure 1 is a vertical sectional view of a

preferred embodiment of the invention, the illustration being somewhat diagrammatic.

Fig. 2 is a plan view of the same.

Fig. 3 is a detail perspective view of a piece of flong.

Fig. 4 is a similar view of a finished matrix made from such a piece of flong.

I wish to emphasize that the mechanism displayed herein as a suggestion of suitable apparatus is to be understood and interpreted in its broadest aspect, inasmuch as it is obvious that the details of construction and mode of operation may be varied extensively or carried out in practice in various modes so long as the broad principle 70 of the invention is not departed from.

Making now a more specific description of the mechanism illustrated, I show at 10 a base adapted to support for rotation around a vertical axis a platform or turn table 11 shown as provided with a vertical journal 12 located in the bearing 13 made as a part of the base. For convenience the turn table is shown as of circular form in plan view and provides seats for a plurality of type 75 forms and units of operation, these seats being indicated at A, B, C, and D. While I have shown four, a variable number of such seats might be provided. It will be understood that these seats are large enough in 80 scope to accommodate type forms 14, 15, 16, and 17, sufficiently large for newspaper work or any other size matrix that may be desired to be made from the type forms.

18 represents diagrammatically the face 85 of a type form of any suitable matter set up from type, cuts, or the like suitable for reproduction in the matrices and for printing as a result of the making of the matrices.

M indicates a motor of any suitable type 90 or construction adapted to be started and stopped automatically by means of a start and stop switch mechanism at 19. The intervals or dwells and operation of the motor may be timed according to the nature of the work, but it may be assumed that the dwells may be approximately sixty seconds.

The turn table is caused to rotate around its vertical axis by any suitable means preferably a roller 20 journaled in upright extensions 21 and 22 of the base. To the horizontal shaft 23 of the roller there is attached a driving member such as a belt pulley 24 operated at relatively low speed from the high speed motor shaft through a belt 25 105 110

and pinion 26. The surfaces of the roller 20 and the underside of the turn table are so correlated as to cause the driving of the turn table with the least amount of friction. 5 This operation is assisted by means of a second roller 27 having an inclined axle 28 journaled at 29 in the extension of the base and at its inner end in an arm 30. The upper roller 27 is so located as to have co-operation as soon to be described with the work carried by the upper surface of the turn table, and preferably the lower side of the roller 27 is horizontal so as to co-operate directly with the flat forms carried by the 10 15 turn table.

The upper roller may be actuated in any convenient manner but as shown it is driven by a pair of beveled gears 31 and 32 connected to the respective roller shafts. Consequently when the lower shaft is rotated, the upper shaft and its roller will be rotated and at the same speed. Each roller constitutes a resistance for the pressure applied to the turn table by the other roller and they 20 25 co-operate, moreover, to drive effectively the turn table between them.

33 indicates a strip or section of flong which is a piece of plastic material such as is commonly used for matrix making purposes. This body of material, though moist, is of sufficient firmness and strength to be handled, and so it is placed upon the type face 18 in form 14 at the seat A, it being understood that the operator stands at the side 30 35 of the turn table represented by the bottom of Fig. 2. The direction of rotation of the turn table is counter clockwise or as shown by the arrow. Immediately after the flong is put upon the type face 18, the rotation 40 of the table brings this form 14 with the flong thereon into engagement with the roller 27, the effect of which is to force the mass of plastic material into proper place upon, into, or among the type faces 45 and to express any surplus of moisture therefrom which may be collected or disposed of in any convenient manner. The table thence continues to rotate step by step until the piece of flong under consideration 50 55 is cured to a dry matrix 34 and thus returns with the form 14 to its original seat.

The turn table is made of a material suitable for receiving a sufficient degree or quantity of heat for the purpose of drying the piece of flong while it passes in its circuit past the seats B, C, and D, back to its start-

ing point. Any suitable means may be provided for heating the turn table and flong. I indicate for this purpose a gas burner 35 extending along approximately one-half of the scope of the turn table, the heat from the burner being caused to play directly against the under surface of the turn table, thereby heating the same and the devices carried thereby. 60 65

The type forms 14, 15, 16, 17, may be all the same or different as may be desired. The operator, however, manipulates the flongs upon the several type forms in succession as the seats come in rotation within his reach. That is to say, as indicated herein, the flong will be placed upon the form 14 at the seat A and directly thereafter another seat or form 15, or 16, or 17, will be brought into reach of the operator who will remove 70 the dried matrix 34 therefrom and will place another flong upon the same to perform upon which the dried matrix was so formed and so removed. The dwells or intervals of time of rest between successive actuations of the table will be understood to be just long enough to permit the operator to make this interchange. Furthermore, the heat of the turn table will be so determined as to be sufficient to cause the thorough drying of 75 80 the flongs into the making of matrices while they pass from the expressing roller 27 around to the station or seat A. Thus it will be noted that the process is rapid, relatively easy, and efficient. 85 90

I claim:

A machine for making stereotype matrices in a continuous circulating operation comprising a support having a plurality of seats thereon for receiving and holding a plurality of type forms upon which a like number of flongs may be placed in succession from a fixed position, means to actuate the support along a continuous path, means to operate upon the flongs in succession to cause the same to be properly molded in connection with the type forms while in motion, and means to cause the hardening of the flongs after such molding operation as they pass in succession along said path without the aid of human factors after the flongs have been placed upon the face of the type forms and are returned in succession to said fixed position. 95 100 105

In testimony whereof I affix my signature.

GROVER M. REPP.
